US00D810011S

(12) **United States Design Patent** (10) **Patent No.:** **US D810,011 S**
(45) **Date of Patent:** **** Feb. 13, 2018**

(54) **BATTERY**

(71) Applicant: **BRIGHTVOLT, INC.**, Lakeland, FL
(US)

(72) Inventors: **Craig Nelson**, Melbourne, FL (US);
Robert W. Singleton, Plant City, FL
(US); **Michael G. Scruggs**, Lakeland,
FL (US); **Wade W. Guindy**, Henderson,
NV (US)

(73) Assignee: **BrightVolt, Inc.**, Redmond, WA (US)

(**) Term: **15 Years**

(21) Appl. No.: **29/555,097**

(22) Filed: **Feb. 18, 2016**

Related U.S. Application Data

(60) Continuation of application No. 14/949,013, filed on Nov. 23, 2015, which is a continuation of application No. 12/466,900, filed on May 15, 2009, now Pat. No. 9,224,516, which is a division of application No. 11/187,440, filed on Jul. 22, 2005, now abandoned.

(57) **CLAIM**

The ornamental design of a battery, as shown and described.

DESCRIPTION

FIG. 1 is a top perspective view of a battery in accordance with the present invention.

FIG. 2 is a top view of a battery in accordance with the present invention.

FIG. 3 is a left side view of a battery in accordance with the present invention.

FIG. 4 is a right side view of a battery in accordance with the present invention.

FIG. 5 is a back view of a battery in accordance with the present invention; and,

FIG. 6 is a front view of a battery in accordance with the present invention.

(Continued)

The bottom of the battery is flat and devoid of surface ornamentation.
